UNITED STATES PATENT OFFICE

138,561

DESIGN FOR A COFFEE MAKER OR THE LIKE

Peter Schlumbohm, New York, N. Y., assignor to Chemex Corporation, New York, N. Y., a corporation of New York

Application March 10, 1944, Serial No. 112,861

Term of patent 14 years

(Cl. D44—26)

To all whom it may concern:

Be it known that I, Peter Schlumbohm, a citizen of the German Republic, but having filed my second papers for U. S. citizenship, residing at New York, in the county of New York, and State of New York, have invented a new, original, and ornamental Design for Coffee Maker or the like, of which the following is a specification, reference being had to the accompanying drawing, forming part thereof.

Fig. 2 is a side view in elevation;

Fig. 3 is a top plan view; and

Fig. 4 is a bottom plan view.

I claim:

The ornamental design for a coffee maker or the like, as shown.

PETER SCHLUMBOHM.
